HERMAN B. KIPPER, OF MUSKEGON, MICHIGAN.

METHOD OF PROTECTING METAL HEATED TO A HIGH TEMPERATURE AGAINST OXIDATION.

1,358,161.

Specification of Letters Patent.

Patented Nov. 9, 1920.

Application filed May 19, 1919. Serial No. 298,118.

To all whom it may concern:

Be it known that I, HERMAN B. KIPPER, a citizen of the United States of America, residing at Muskegon, in the county of Muskegon and State of Michigan, have invented certain new and useful Improvements in Methods of Protecting Metal Heated to a High Temperature Against Oxidation, of which the following is a specification.

- 10 The present invention relates to a method of producing cyanids or nitrogenous compounds through the action of nitrogen gas on a mixture of sodium carbonate or other sodium salts, carbon and iron.
- 15 It has been known for a number of years that if sodium carbonate, coke and iron are heated together to about 900 to 1000° C. and nitrogen or producer gas is passed through the heated mass, sodium cyanid and other 20 sodium nitrogenous compounds are formed. If through the mass of compounds thus formed at the higher temperature, steam is passed at a temperature of about 400° C., ammonia is formed, possibly somewhat according to the following reaction:—

This knowledge notwithstanding, the process has never been successfully commercially developed. The reason for this is that the process must be carried out in a closed metal vessel at a temperature of 900 to 1000° C. and that in heating a metal vessel to such temperature by an ordinary fire the excess 35 oxygen left in the gases will cause rapid oxidation and destruction of the metal.

The chief object of my invention is to obviate this drawback, that is to say, to heat the vessel so that while the desired temperature for the formation of nitrogenous compounds can be retained for almost any length of time, oxidation and consequent destruction of the metal vessel will be prevented.

45 To accomplish this object my invention consists chiefly in that the metal reaction vessel is heated to about 1000° C. over a high column of coke or coal, the combustion of which is directed in such a way that a heating gas is produced which consists of a mixture of nitrogen and carbon monoxid (CO) with but a minimum percentage of carbon dioxid.

55 The metal reaction vessel contains the mixture of sodium salt such as sodium carbonate, iron and coke and through it is passed either

nitrogen or producer gas, that is, one composed of carbon monoxid and nitrogen, and at either atmospheric or superatmospheric pressure I find that at high pressures the 60 nitrogen more readily combines with the sodium salts so that lower heating temperature may be used and consequent better protection of the reaction vessel is secured.

By admixture of potassium salts I have 65 also found that the reaction temperature is lowered.

By burning a layer of coal, as for instance with ordinary steam boilers, the oxygen of the air passing through the coal bed burns the combustible portion of the latter mostly to carbon dioxid. By using a higher bed of coal or coke the oxygen of the air in passing through it is almost fully consumed to form carbon dioxid. In the upper portion of the bed, however, the carbon dioxid in the presence of the hot coal or coke is decomposed or reduced to form carbon monoxid according to the following chemical equation:—

80

The carbon monoxid thus produced can be conveniently used as a fuel gas.

In all ordinary processes of combustion, the oxygen of the air, of which there is about 20%, alone acts chemically while the 80% of the nitrogen gas contained in the air remains practically inactive chemically and acts therefore merely as a diluent.

In burning carbon (coke or coal) to carbon monoxid only part of the total heat of chemical reaction is evolved, thus:

95

It will thus be seen that all the energy of the combustion of the coal or coke is not utilized directly in heating the cylinder in which the cyanid compounds are formed. The carbon monoxid, or producer gas, may, 100 however, be withdrawn and used for other purposes, such as drying, heating of the cyanid to 400° C. before passing steam through it, and might be employed for any other purpose in which gaseous fuel can be 105 advantageously used.

It is known that at high temperature carbon dioxid is dissociated or decomposed into carbon monoxid and oxygen. I therefore attempt to keep the percentage of carbon dioxid formed during combustion as low as possible.

While I do not wish to confine myself to any specific form of apparatus, I shall describe herein one form which has proved to be the simplest devisable and which can be 5 recommended for carrying out the process on a large scale.

In the accompanying drawing the apparatus is more or less diagrammatically illustrated.

- 10 *a* denotes a producer similar to an ordinary gas producer and made of steel plate in a rectangular shape. This is lined first with insulating brick as at *b* and then with fire brick as at *c*. In the upper portion of 15 this apparatus one or more cylinders *d* made of heavy wrought iron pipe or any suitable metal or alloy are placed. These cylinders may be arranged in any suitable manner to be revolved.
- 20 Through the cylinder *d* a mixture of sodium salts, such a sodium carbonate, iron and coke and nitrogen or producer gas are passed. The producer is filled with a high column of coke or coal and at the bottom 25 of the producer an air inlet *e* is provided through which an amount of air is passed through the coal or coke bed which amount is in a suitable proportion to the column of carbon so as to form a heating gas consist-
- 30 ing chiefly of carbon monoxid with a minimum amount of carbon dioxid. The combination of the coke or coal will, as stated

before, furnish a heating gas consisting of carbon monoxid and only a very small percentage of carbon dioxid, which gas will 35 heat the vessel *d* to the desired temperature without causing its oxidation.

In order to prevent clinkering we have most advantageously used an ashless fuel such as petroleum coke.

40 What I claim and desire to secure by Letters Patent is:—

1. In the process of producing nitrogenous compounds by heating a mixture of sodium salts with carbon and iron in a metal 45 vessel to a high temperature and passing nitrogen or producer gas through said vessel, the step of protecting the metal vessel from oxidation, consisting in heating said vessel by burning a carbonaceous fuel to 50 carbon monoxid and a minimum of carbon dioxid, and preventing excess of oxygen.

2. The herein described method of protecting metal heated to high temperature from oxidation, consisting in heating said 55 metal by burning a carbonaceous fuel to carbon monoxid and a minimum of carbon dioxid, and preventing excess of oxygen.

In testimony whereof I affix my signature in presence of two witnesses.

HERMAN B. KIPPER.
